UNITED STATES PATENT OFFICE.

EDWIN F. HULBERT, OF MILWAUKEE, WISCONSIN, ASSIGNOR, BY MESNE ASSIGNMENTS, TO THE MASTER PACKAGE CORPORATION, OF DELAWARE.

CONTAINER CLOSURE AND METHOD OF MAKING THE SAME.

Application filed October 21, 1925. Serial No. 63,906.

The invention relates to containers, and more particularly to fibre containers, and the method of making and securing the bottom head to the siding forming the body 5 or cover of such containers.

The object of the invention is to provide a fibre container with a dished head which is firmly and efficiently secured to the siding of the container by means of a metal 10 band which is combined with the siding and the head by the method hereinafter described.

The invention further consists in the several features hereinafter set forth and more 15 particularly defined by claims at the conclusion hereof.

In the drawings Fig. 1 is a vertical sectional view through a container embodying the invention;

20 Fig. 2 is a detail sectional view showing the initial position of the parts in the forming apparatus before attaching the head;

Fig. 3 is a detail sectional view showing 25 an intermediate position of the parts in the forming apparatus during the attachment of the head;

Fig. 4 is a detail sectional view showing 30 the final position of the parts in the forming apparatus.

The subject-matter of the invention relates to the method and means employed in connecting the head to the siding of the head or cover of the container, and since 35 it is equally applicable for either the cover or the body of the container, the container alone has been shown in detail for the purpose of explaining the invention.

The siding 5 for the container is of fibre tubing, either of pressed pulp or a number 40 of wrappings of paper or fibre sheets, and is generally in the form of cylindrical or conical tubing.

The head 6 is of fibre, consisting of one or more paper or fibre sheets or laminations, 45 with one or more of these laminations bent at an angle adjacent its edge to form a dished or flanged head.

The metal sheathing and clamping band 7, 50 preferably of thin sheet-steel or other suitable sheet-metal, is made up in the form of a band, having an inwardly extending base flange 8 and a slightly curved outer edge 9.

To secure the above named parts together

the siding 5 is placed over an anvil 10, preferably in the form of an expandible chuck, which firmly grips the interior of the siding and forms a support for the cover. The siding is clamped between this anvil and an external contractible chuck 11. The 55 dished head 6, with the flange 12 extending upwardly, is placed in position shown in Fig. 2; with the upper part of the flange extending beyond the edge of the siding, and the band 7 is placed in position on top 60 of said head and within the flange. A cylindrical plunger 13 is then moved down so as to clamp the head between it and the anvil 10 and also clamp the base flange to the head, this plunger having an annular 65 recess 14 formed therein to provide a space 15.

The chuck 11 and the plunger 13 cooperate to form an annular space 16, the sides 17 of the chuck at the lower end of 70 this space being curved inwardly toward the siding. A cylindrical plunger 18, having an annular portion 19, moves in the space between the chuck 11 and the plunger 13, 75 and has a curved lower edge.

With the head and the siding clamped in the position shown in Fig. 1, the plunger 18 is moved downwardly and exerts a pressure against the parts, thereby curling or bending the upper edge of the band and the 80 flange over the upper edge of the siding, as shown in Fig. 3, and finally bending the siding with the band and flange into a beaded edge and forcing the band and flange laterally into the space 15 to firmly clamp the siding and the flanged portion of the siding 85 between opposite sides of the band, thereby securely locking the band in position with the base flange 8 of the band firmly held against the dish portion of the head 90 and providing a firm support therefor, particularly when this head forms the bottom of the container. The lateral displacement of the reinforced beaded edge is important as it provides an interlock, and the siding and flange are firmly gripped between the in-turned edge 20 of the band and in-turned edge 21 formed by the angle between the base flange 8 and the convolute part 22 of the band adjacent thereto.

What I claim as my invention is:

In a container, the combination with the siding, of a dished head having a disk por-

tion and the dish portion fitting within the head, said dished portion having a flange extending beyond the outer side of the disk portion of said head and bent laterally with
5 said siding inwardly over the disk portion of said head, of a metal band having an annular base portion engaging the head and a portion extending above and outwardly from the outer edge of said base portion over said flange and the bent-over part of said 10 siding.

In testimony whereof, I affix my signature.

EDWIN F. HULBERT.
